UNITED STATES PATENT OFFICE.

JOHN B. BARTHOLOMEW, OF PEORIA, ILLINOIS, ASSIGNOR TO AVERY COMPANY, OF PEORIA, ILLINOIS, A CORPORATION OF ILLINOIS.

GANG-PLOW.

1,379,673.

Specification of Letters Patent. Patented May 31, 1921.

Original application filed May 15, 1913, Serial No. 767,923. Renewed October 12, 1916, Serial No. 125,288. Divided and this application filed May 4, 1917. Serial No. 166,367.

To all whom it may concern:

Be it known that I, JOHN B. BARTHOLOMEW, a citizen of the United States, residing at Peoria, in the county of Peoria and

5 State of Illinois, have invented certain new and useful Improvements in Gang-Plows, of which the following is a specification, reference being had therein to the accompanying drawing.

10 This invention relates to improvements in gang plows and especially to improvements in gang plows in which the furrow-forming elements are disks.

In my application, Serial No. 767,923, 15 filed May 15, 1913, renewed October 12, 1916, Serial No. 125,288, of which the present application is a division, I illustrated and described a plowing mechanism in which the present improvements can be embodied,

20 upon which application Letters Patent 1,227,237 were issued May 22nd, 1917. The object of these improvements is to provide means for supporting the frame which carries the disks, which will permit the disk-

25 carrying part of the frame to be readily lifted out of plowing position, and which can then be held in relation to the frame so that it can be transported from place to place as desired. The frame has an inclined draft bar for attaching the disks in diagonal series and it is supported at the front and at the rear in such a way that it can be raised first at the rear end, and afterward at the front end, and can then be rigidly connected to its supporting devices for the purpose set forth.

30 Other objects will be apparent from the following description.

35 In the accompanying drawings I have shown the embodiment of my invention which I now deem preferable. It will be understood, however, that numerous changes and modifications may be made.

40 Of the drawings:

45 Figure 1 is a plan view of the entire plow;

Fig. 2 is a side elevation;

Fig. 3 is a rear elevation;

50 Fig. 4 is a fragmentary side view, partly in section, of the forward right-hand supporting wheel and associated parts;

55 Fig. 5 is a fragmentary diagrammatic plan view of one of the rear supporting wheels and associated parts;

Fig. 6 is a fragmentary diagrammatic rear elevation of the parts shown in Fig. 5 with the frame in normal operative position;

Fig. 7 is a view similar to Fig. 6, but 60 showing the frame in elevated position;

Fig. 8 is a fragmentary sectional view taken along the lines 8—8 of Fig. 1;

Fig. 9 is a fragmentary sectional view taken along lines 9—9 of Figs. 1 and 8; and 65

Fig. 10 is a fragmentary diagrammatic view of the lifting cams taken from the right-hand side of the machine.

Referring to the drawings, it will be noted 70 that the main frame as shown, comprises two principal parts, 1 and 2. As to the details of these frame parts, there may be variations, but in the construction shown the forward part, 1, comprises a front cross bar 3, and the side bars 4 and 5. The side bar 4 extends rearward throughout a part of its length and is then bent inward to form the diagonal member 4^a. The side bar 5 extends rearward for a short distance and is then bent inward to form the diagonal element 5^a. The rear ends of the diagonal elements 4^a are joined at 6.

The rear frame section 2 comprises a forward member 7 which is diagonally positioned parallel to the diagonal element 4^a of the front frame. The frame section 2 also has a diagonal element 8 which is connected at its forward end to the rear end of the element 7 and which is positioned 85 parallel to the element 5^a of the front frame. A strut or brace 9 connects the forward end of the element 7 with the rear part of the element 8.

The two frame sections are flexibly connected together by means of hinge devices 90 at 10 and 10^a.

While I have shown in the drawings but two frame sections, it will be understood 100 that a larger number of sections may be used if found desirable. The manner of constructing and connecting such additional frame sections will be readily apparent.

Rigidly secured to the diagonal rear edge elements 5^a and 8 of the frame sections 1 and 105 2 are plowing or furrow-forming elements 11—11. As shown, these plowing elements are rotatable disks which are connected to the frame parts by means of brackets 12—12. The disks can be connected to the brackets 110

in any well-known or preferred manner, and as this feature of the mechanism forms no part of my present invention, detailed description can be omitted. As shown, the 5 disks 11—11 are provided with scrapers 13—13, but as to this feature also, there can be variation. In fact, so far as certain features of my invention are concerned, the disks may be omitted entirely and plowing 10 elements of moldboard type substituted.

For supporting the forward corner of the front frame section, which is opposite to the plowing elements, I provide a ground wheel 14 rigidly secured to a rotatable shaft 15. This shaft 15 is mounted in a bearing 16, secured to the frame member 4 and in a bearing 17, secured to a supplementary frame member 18, which extends from the front member 3, rearward, to the point of 20 connection between the members 4^a and 5^a. For supporting the opposite forward corner of the front frame section, I provide a ground wheel 19, which is loosely mounted on the axle 20. The axle 20 is connected 25 with the vertical spindle 21, which is vertically slidable in a bearing aperture in a pedestal 22, secured to the frame element 5. Mechanism is provided for moving the spindle 21, together with the axle 20 and the 30 wheel 19, vertically with respect to the bracket. This mechanism will be herein-after described in detail. For preventing the axle 20 and the wheel 19 from swinging about the axis of the spindle 21, I provide 35 the link or strut 23, which can be adjusted in length by means of the turnbuckle 24. In this way the axle 20 can be moved, and the angle of the wheel, with respect to the line of draft, can be varied as desired. The 40 lifting of the frame relative to the wheel 19 does or may exert a pull on the link 23 to slightly swing the wheel forward, but this movement will not be of great extent and will not interfere with the handling 45 of the machine. The adjustment by the turnbuckle 24 will be such as to maintain the wheel in the desired position during plowing.

For supporting the rear part of the front frame section, I provide the third ground wheel 25, which is positioned at an angle to the vertical and so located that it is adapted 50 to travel in the furrow formed by the last disk on the front frame section. This wheel 25 is mounted on an axle 26 which is connected to the vertical spindle 27. This spindle 27 is slidable in a vertical bearing aperture in a pedestal 28, which is secured to the frame by means of the bracket 29. 55 In the form shown, this bracket 29 is an extension of the bracket 12 for the rear disk. As to this feature, there can be variation. Preferably the bracket 29 is reinforced by the bar indicated at 30. The spindle 27, 60 together with the axle 26 and the wheel 25,

can be moved vertically with respect to the frame by means of mechanism similar to that for the spindle 21. This mechanism will be described later.

The forward parts of the rear frame section 70 2 are supported by means of the hinges 10 and 10^a which connect them to the front frame section. The rear part of the rear frame section is supported by means of a ground wheel 31, which is mounted by means 75 of an axle 32 and a spindle 33, similar respectively to the parts 26 and 27. The spindle 33 is mounted in a pedestal 34 which is similar to the pedestal 28 and is similarly secured to the frame section. The wheel 31 80 can be moved vertically with respect to the frame section by mechanism to be described.

Secured to each of the pedestals 22, 28 and 34, is a horizontally extending arm 35 to which is pivotally connected the lower 85 end of a threaded rod 36. 37 is a yoke which is slidable on the rod 36 and which can be adjusted by means of the threaded hand wheel 38. 39 is a lever which is bifurcated at its rear end and embraces the 90 sleeve 40 secured to the upper end of the spindle. The lever is pivoted to the sleeve at 41. The rear end of the lever is pivoted at 42 to the yoke 37, and a lug 43 on the sleeve 40 serves to limit the movement of 95 the lever in one direction. From the foregoing description it will be obvious that the downward movement of the forward end of the lever will cause a corresponding downward movement of the spindle and of the 100 wheel and axle with respect to the pedestal. However, as the wheel is in contact with the ground, the result will be a lifting of the pedestal and of the adjacent frame parts with respect to the wheel. The relative 105 positions of the wheel and of the frame parts can be adjusted by means of the hand wheel 38. For holding the pedestal and frame parts in lifted positions, I provide a spring held latch 44 which is adapted to engage a suitable lug on the sleeve 40. Each latch 44 is held by its spring either in operative or inoperative position, as desired by the operator. When it is desired to hold 110 the disks in elevated position, the latches are 115 manually thrown into their operative positions.

The controlling lever for the front wheel 19 is indicated, as before noted, by 39. The lever for the middle wheel 25 is indicated 120 by 39^a. The lever for the rear wheel 31 is indicated by 39^b. These levers can be operated manually by the plowman, but I prefer to also provide means whereby the levers can be moved automatically by power and moved successively. As to the details of this lifting mechanism, there can be wide variation, but for the purpose of illustration, I have shown a mechanism which is in many respects similar to that shown and de- 125 130

scribed in my earlier co-pending application for gang plows, Serial No. 671,955, filed January 18, 1912.

Referring in detail to the lifting mechanism, 45 is a short jack shaft parallel to the shaft 15, upon which the ground wheel 14 is mounted. Loosely mounted on the jack shaft 45 is a sprocket wheel 46 in line with a sprocket wheel 47 on the shaft 15. A chain 48 passes over these two wheels. Secured to the sprocket wheel 46 is a notched or serrated disk 49, and adjacent this disk and keyed to the shaft 45 is a large circular disk 50 formed at one point in its periphery with a rounded notch 51. A dog 52 is pivotally mounted on the disk 50. The head of the dog carries a laterally extending roller 53 arranged to engage with the notched periphery of the disk 49, and a spring 54 which is interposed between the hub of the disk 49 and the dog 52, tends to press the roller 53 into engagement with the disk 49. A lever 55 is pivotally mounted on the bearing bracket 56 beneath the disk 49 and carries a roller 57 adapted to ride upon the periphery of said disk. The lever also carries the roller 58 which is disposed in the plane of the dog 52. 59 is a coil spring interposed between the end of the lever 55 and an extension 60 of the bearing bracket 56, and tends to press the roller 57 radially inward against the disk 50. The upper end of the lever 55 has connected to it a rope or cord 61, which extends forward to some convenient point within the reach of the operator.

By referring to Fig. 8 it will be seen that when the roller 57 lies within the notch 51 in the disk 50, the roller 58 is in position to engage the rounded back or tail of the dog 52 and swings the dog on its pivot so that the roller 53 is withdrawn from engagement with the continuously rotating notched disk 49. If now the driver pulls on the rope 61 to swing the upper end of the lever 55 forward, the rollers 57 and 58 will be swung downward and the spring 54 will expand and cause the dog 52 to swing the roller 53 into engagement with the rotating disk 49. In this way a driving connection is effected between the disk 49 and the disk 50, so that the rotation of the former is transmitted to the latter.

The rotation of the disk 50 causes the notch 51 to be immediately moved away from the roller 57 so that when the rope 61 is released by the driver and the spring 59 tends to return the lever 55 to its initial position, such a return is prevented by the engagement of the roller 57 with the circular periphery of the disk 50. But as the disk 50 nears the end of its revolution, the roller 57 rides suddenly into the notch 51 under the action of the spring 59, and in this movement the roller 58 is caused to strike the tail

of the dog 52 and to cause the disengagement of the roller 53 from the disk 49.

Thus, by a simple pull upon the cord 61, the rotation of the disk 50 is started, and at the end of a single revolution is automatically stopped. Connected to the disk 50 and to the shaft 45 is a sprocket wheel 62 which is in line with a sprocket wheel 63 on a transverse shaft 64 at the forward end of the frame. 63^a is a chain passing over the sprocket wheels 62 and 63. This shaft 64 is mounted in suitable bearings secured to the brackets 65, 66 and 67 mounted on the front member 3 of the frame. The ratio between the diameters of the sprocket wheels 62 and 63 is such that the shaft 64 is given a half revolution for every complete revolution of the shaft 45. Each of the brackets 65, 66 and 67 is formed in two parts, and between the parts of the several brackets there are mounted cams 68, 69 and 70. Pivoted to the forward outer ends of the brackets 65, 66 and 67 are levers 71, 72 and 73 which carry rollers 74, 75 and 76 adapted to engage, respectively, with the cams 68, 69 and 70. Connected to the rear end of the lever 71 is a chain 77 which extends over a suitable pulley 78 and is connected to the spindle 21. A chain 79 is connected to the rear end of the lever 72. This chain extends over suitable pulleys 80 and 81 and is connected to the lever 39^a for the wheel 25. A chain 82 is connected to the rear end of the lever 73. This chain extends over suitable pulleys 83, 84 and 85, and is connected to the lever 39^b for the rear wheel 31.

Each of the cams 68, 69 and 70 is formed with an active lifting portion 86, an inactive sustaining portion 87 and an inactive dropping portion 88. It will therefore be clear that as each cam rotates, it engages the corresponding rollers to swing the corresponding lever and move the corresponding wheel downward with respect to the frame. After the movement of the lever is once effected, the lever will be held in lifted position during the next succeeding part of the rotation of the cam. Upon further rotation of the cam, the lever will be released and permitted to return to the lower position, as shown in Fig. 2.

The cams 68, 69 and 70 are angularly spaced on the shaft so that during rotation the cam 68 first comes into action, then the cam 69, and finally the cam 70; this resulting in first lifting the forward disks of the front diagonal series or group and then lifting those at the rear end of the series, and in lifting the groups successively, the furrow wheels being successively released from their locks or holders and allowed to caster after the rear disks of their respective groups have been raised. It will be understood from the foregoing description that the shaft 64 is rotated through a half revolution

lution at each actuation of the clutch. During one half-revolution the active parts of the cams are brought into engagement with the rollers, and the three wheels 19, 25 and 5 31 are moved successively to cause a successive lift of the adjacent parts of the frame and of the adjacent plowing elements. At the end of the first half-revolution the rollers are still engaged by the cams, and the 10 frame parts and plowing elements are maintained in lifted positions. During the next half-revolution the cams successively disengage the rollers and permit the levers to move and release the frame parts and 15 plowing elements, and permit them to return successively to plowing position.

The plow, as a whole, can be hauled in any approved manner, as by means of a suitable tractor, or tractor engine. Chains 20 89—89 are provided for the hauling of the plow. To facilitate the turning of the plow, as a whole, at the ends of the furrows, or at the corners of a field, the wheels 25 and 31 are so mounted that they can swing 25 laterally when the frame sections are in lifted positions. It will be noted that lugs 90 and 91 are provided which serve to hold the wheels against swinging when the frame sections are in plowing position. However, 30 these lugs disengage the wheels when the frame sections are lifted and free movement of the wheels is therefore possible.

As before pointed out, the wheel 19 can be adjusted angularly so as to tend to a 35 greater or less extent to move the plow laterally and to hold the plowing elements up to their work.

What I claim is:—

1. In a gang plow, the combination of a 40 frame, a diagonally arranged series of plowing disks rigidly connected to the frame, two wheels for supporting the forward part of the frame, a disk alining furrow wheel adapted to caster and connected with and 45 supporting the rear part of the frame, optionally active means actuated by one of the wheels at the front of the frame, power transmitting devices driven by said means and arranged to first lift the front part of 50 the frame and the front disks of the series and thereafter lift the rear part of the frame and the rear disks of the series, and means for locking said furrow wheel against castering and holding it as a rigid disk 55 alining wheel until the front disks have

been raised, and then automatically releasing said wheel and permitting it to caster after the rear disks are raised.

2. In a gang plow, the combination of the plurality of flexibly connected frame 60 sections, each having a diagonally disposed rear edge part, and each section being, on the land side, supported above the ground, a plurality of groups of plowing disks, the disks of each group being arranged in a 65 diagonal series and fixedly connected to the rear edge part of a frame section, two front wheels for supporting the forward part of the front frame section, a disk-alining furrow wheel for supporting the rear end 70 of the diagonally disposed edge part of each frame section and adapted to caster, power transmitting devices adapted to be optionally actuated by one of the front frame-supporting wheels and adapted to 75 first lift the front disks of each group and thereafter lift the rear disks of said group, and also adapted to lift the groups successively, and means for holding the furrow wheels against castering when the disks 80 are in their lowered positions, and for releasing each furrow wheel and permitting it to caster after the rear disks of its group have been elevated, and releasing the furrow wheels successively. 85

3. In a gang plow, the combination of supporting front ground wheels, a frame carried by said wheels and comprising a plurality of independently movable plow beams, plowing elements carried by said 90 beams, a supporting ground and caster wheel on the rear end of each of said plow beams and having a substantially vertical pivot, means for limiting the turning of each of the caster wheels on its pivot when 95 the frame is lowered, power mechanism adapted to successively release the caster wheels from said limiting means during one cycle of operation to permit the successive turning of the caster wheels, and a clutch 100 whereby said power mechanism may be connected with a rotary power element to cause the operation of said mechanism.

In testimony whereof, I affix my signature, in presence of two witnesses.

JOHN B. BARTHOLOMEW.
